DESIGN.

—o—
D. G. MELVILLE.

CARPET.

No. 16,137.

Patented June 23, 1885.

UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 16,137, dated June 23, 1885.

Application filed April 25, 1885. Term of patent 3½ years.

To all whom it may concern:

Be it known that I, DAVID G. MELVILLE, of Medford, in the county of Middlesex and State of Massachusetts, have invented a certain new and original Design for a Carpet, of which the following is a specification.

The nature of my design is fully shown in the accompanying photographic illustration.

The design consists in the variously-formed and thickly-arranged leaves and flowers, as shown.

I claim—

The design for a carpet, substantially as shown and described.

In testimony whereof I have signed my name to this specification, in the presence of two subscribing witnesses, this 17th day of April, 1885.

DAVID G. MELVILLE.

Witnesses:

WALTER S. GADSBY,
DAVID McNAIR.
